KNOCKDOWN BASKET AND SIMILAR
CONTAINERCharles H. Goodyear, Portland, Oreg., assignor of
one-half to Frank C. Stettler, Portland, Oreg.

Application June 23, 1932, Serial No. 618,881

1 Claim. (Cl. 229—16)

My invention has for its object the providing of an inexpensive basket, or container, stamped out as a one-piece blank from a thin resilient sheet, preferably paper-board; adapted to be set up readily, and when set up having its sides upheld by a simple hoop, preferably of wire, sprung into notches provided for it at the corners formed by the walls of the basket. Said hoop thus being held in place by the resiliency inherent in the material, tending to spring the sides of the set-up basket outward.

Such a basket is especially serviceable for holding vegetables and fruit. The cost of the material and of cutting out the blank for my basket is small; and the setting up of the basket is so simple that it can be done by anyone in a moment. It merely requires the sides of the basket to be arranged upright, the hoop then slipped over the sides into said corner notches, and the basket is ready for immediate use.

Incidentally, by reason of my basket being so readily set up, it is not necessary to set up quantities of the basket in advance of requirement; thus my basket may be stored as a flat package of blanks and the basket set up as required. The blanks of my basket take up very little room on the counter and are not in the way as would be a stack of set-up baskets.

I attain the objects of my invention by the particular type of blank shown in the accompanying drawings, such blank being adapted to be set up with the wall portions upheld by means of a hoop secured in place, as above mentioned, and hereinafter more fully explained.

35 In the accompanying drawings:

Fig. 1 shows a perspective view of the preferred type of my basket;

Fig. 2 shows the blank for making this type of basket;

40 Fig. 3 is an enlarged side elevation of said type of my basket;

Fig. 4 is a section on the line approximately pointed to by the arrow 4 in Fig. 1;

Fig. 5 is an enlarged fragmental plan section approximately on the line 5 pointed by the arrow 5 of Fig. 3; and

45 Figs. 6 to 11 inclusive illustrate variations in the shape of my basket, and the blanks for making the same.

50 Referring first to Figs. 1 to 4 inclusive; the blank of my basket shown by Fig. 2 consists of a bottom section *a* and sidewall sections *b*, *c*, *d* and *e*. The side-wall sections *d*, *e* are made with flaps *f*, *g* and *h*, *i*, respectively. The lateral edges of wall-sections *b*, *c* are given an outward flare, as

shown by *b'*, *c'*, in Fig. 2, and the parts are scored, as at *j*, so that the parts may be readily bent in setting up the basket.

The corners formed by the wall sections *d*, *e* and their flaps *f*, *g* and *h*, *i* are provided adjacent the top with notches *k* arranged to be disposed in a horizontal plane, thus parallel with the bottom section *a* when the basket is set up. The wall-sections *b*, *c* constitute spacing elements; their corners are cut away as at *b2* and *c2* to coincide with the notches *k*.

The cut-out spaces 1 merely represent air holes for the basket.

The hoop *m*, preferably made of wire, for the type of basket shown by Fig. 1 will be shaped rectangular with its perimeter slightly smaller than that of the basket. Thus, since the material of which the blank is made is resilient, and the tendency of the wall-sections of the basket when set up is to spring outward, the restraint of such outward spring by the hoop *m* causes the latter, when once seated in the notches *k*, to be firmly held therein.

Further, in the construction shown by Fig. 1, when setting up the basket, the flaps of the side-wall sections *d*, *e* are lapped over the side-wall sections *b*, *c* which thus function as spacing elements holding the side-wall sections *d*, *e* apart. In setting up the basket, and slipping on the hoop *m*, the wall-sections *b*, *c* are slightly bowed inward, and when released tend to spring outward, and in that way hold the hoop *m* firmly in place in the notches *k*.

My invention, however, is not confined in its practical application to the particular type of basket illustrated by Fig. 1, but may equally well be applied to a basket of triangular shape, as shown by Figs. 6 to 8; or of square shape, as shown by Figs. 9 to 11.

If the basket is to be of triangular form, it will consist of a blank shown by Fig. 7, consisting of a bottom section *o* and side-wall sections *p*. The side-wall sections are provided at one lateral edge with flaps *q*. The sections are scored as at *r* to facilitate the setting up of the basket. *s* are notches provided at the corners formed by the side-wall sections *p* with their flaps *q* to receive the wire band *t*, and the corners *p'* of the wall sections *p* are cut away. The basket is held in its set-up form by springing the side-wall sections inward and placing the band *t* in the notches *s*, and the tendency of the wall sections to spring back outward holds the band in said notches; the band *t* being of

slightly smaller perimeter than that of the basket when set up.

- For the type of basket shown by Fig. 9, the blank consists of a bottom section 2, and side-wall sections 3, 3 and 4, 4. The side-wall sections 3, 3 are provided with lateral flaps 5, 5. The blank is scored as at 6 to facilitate setting up, and the side wall sections 3, at the corners formed by their flaps 5, are provided with notches 7 to receive the band 8, and the corners 4' of the wall-sections 4 are cut away. The setting up of this type of basket is similar to the setting up of the basket illustrated by Figs. 1 and 3. The flaps 5 of the wall sections 3 overlap the wall sections 4, the latter functioning as spacers, holding the wall-sections 3, 3 apart. When set up, the tendency of the wall sections to spring back outward maintains the band 8 in the notches 7.
- In either type of my basket the opposite wall-sections may be provided with ears 9 to facilitate handling of the basket.
- Other variations in the form of my basket are self suggestive.

25

The lateral flaps of the wall sections of my baskets for cheaper constructions may be omitted, but add to the stability of my basket and are therefore preferred.

I claim:

A collapsible basket formed of a blank of resilient material foldable to provide a bottom and opposed side and end walls, the end walls having integral extensions to overlie and bear against the outer sides of the side walls when the blank is folded, the juncture of the flaps and end walls being formed with notches near the top edge, and an endless non-stretching band designed to be seated in said notches and overlie the outer surfaces of the side walls, end flaps and end walls, the side walls being cut away at points coincident with said notches to permit those portions of the band lying within the notches to overlie the edge of the side walls at the cut-away portions.

CHARLES H. GOODYEAR.
